CLAIM

The ornamental design for a dental utensil handle, as shown and described.

DESCRIPTION

FIG. 1 is a perspective view of a first embodiment of a dental utensil handle showing my new design;

FIG. 2 is a perspective view of a second embodiment of the dental utensil handle; and,

FIG. 3 is a perspective view of a third embodiment of the dental utensil handle.

The portions shown in broken lines are for illustrative purposes only and form no part of the claimed design.

1 Claim, 2 Drawing Sheets

FIG. 1**FIG. 2**

FIG. 3
